UNITED STATES PATENT OFFICE.

JAMES E. BUSHNELL, OF COLD SPRINGS, NEW YORK, ASSIGNOR TO HYATT ROLLER BEARING COMPANY, OF HARRISON, NEW JERSEY, A CORPORATION OF NEW JERSEY.

MOUNTING FOR CAR-AXLE BOXES.

1,355,639.

Specification of Letters Patent.

Patented Oct. 12, 1920.

Application filed August 2, 1920. Serial No. 400,672.

To all whom it may concern:

Be it known that I, JAMES E. BUSHNELL, a citizen of the United States, residing at Cold Springs, county of Putnam, and State 5 of New York, have invented certain new and useful Improvements in Mountings for Car-Axle Boxes, fully described and represented in the following specification and the accompanying drawings, forming a part 10 of the same.

The present invention relates to certain improvements in the mounting for car axle boxes set forth in my application No. 382,648 filed May 19, 1920, for patent on 15 car axle mountings.

In that prior construction the car axle boxes were secured upon a channel-bar near its opposite ends, and were held at the desired distance apart by the projection of 20 wings upon the boxes into notches cut in the flanges of the channel-bars.

It is the object of the present invention to avoid the labor of cutting such notches in the channel-bars, and at the same time to 25 provide means for holding the boxes securely to the bars, and preferably with clearance between the parts, to permit the self-adjustment of the boxes in line with the axle.

These objects are attained by securing to 30 the bar-flanges at opposite sides of each box, housings which have sockets to engage wings on the box and hold the box to the channel-bar while permitting self-adjustment of the boxes.

The wings are offset toward the lower side of the box so as to clear the flanges of the channel-bar when fitted into the housings.

The housings may be variously constructed to engage the wings detachably, so 40 as to facilitate the assembling of the parts and the separation of the same when required for repairs.

To illustrate this feature two constructions 45 are shown in the annexed drawing, in which the car body is omitted, and only the box-mounting is shown.

Figure 1 is a perspective view of a channel-bar with one of the axle-boxes fitted thereon, and the housing forked or open at the lower side; Fig. 2 is an inverted plan of the parts shown in Fig. 1; Fig. 3 is a cross-section of the channel-bar shown in 50 Fig. 1 on line 3-3 in Fig. 2; Fig. 4 is a

view like Fig. 1 with the housing open at one side; and Fig. 5 is a cross-section of the same at one edge of the socket in the housing.

The channel-bar is formed of a plate *a* with flanges *a'* at its edges; these flanges 60 stiffen the plate and afford attachment of the housings to the bar.

B designates the car-axle, with a car-wheel *C* upon one end. For want of room upon the drawing, the car-wheel is omitted 65 from the opposite end.

The body of the axle-box is designated *D*, and its upper part is fitted between the flanges *a'*, and provided with a seat *b* to rest or bear upon the plate *a*. Such seat 70 is made convex on top, crosswise of the box, so as to rock lengthwise, to adjust itself to the axle and plate simultaneously.

Wings *c* are projected from the sides of the body *D*, below the level of the flanges 75 *a'*, and the housings are attached to the outer sides of the flanges to embrace these wings, and hold the box from longitudinal movement.

The housings have each a foot-plate *d* at- 80 tached to the flanges *a'* by rivets *d'*, and an arm or arms extended downward from the edge of the flange to form the sockets which loosely embrace the wings.

In Figs. 1 to 3 the housing is formed with 85 two arms *h* having a socket *E'* between them to receive the wings of the axle-box.

In these figures, the lateral thrust on the box is resisted by lugs or ears *e* projected from the sides of the body nearly to the 90 flanges.

The box and its wings and lugs are constructed, as shown at *e'*, to clear the flanges *a'* and housings *h*, *h'*, to permit the boxes to adjust themselves automatically to the 95 axle. This construction avoids the necessity of any mechanical adjustments, or the provision of any movable parts to effect adjustments.

A lock-bar *f* is attached to the ends of 100 the arms *h* and touches the under sides of the wings to lock or retain the wings in the housings.

The lock-bars are held in place by cross-bolts *g* which pass through the arms and 105 lock-bars, and extend below the body of the box; thus supporting it firmly.

The box can be taken from the channel-bar by withdrawing the bolts and removing the lock-bars.

The housings sustain the wings beneath the flanges a' and hold the boxes firmly from end-thrust, without cutting into the flanges to form a transverse shoulder.

5 In Figs. 4 and 5 the housing is open at one side and each wing is held in place by the horizontal arm h^2 of the housing along the lower side of the socket E' .

The vertical arm h^2 of the housing resists 10 end-thrust upon the axle, and end-support in both directions is secured by applying the housings to the opposite ends of channel-bar in reverse positions.

In Fig. 5, the seat b' on top of the body 15 D is extended nearly to the inner sides of the flanges a' to resist lateral thrust, and the wings c' are extended out from the ends of the seat to project through the housings.

20 With both the constructions of Figs. 1 to 4 the end-thrust is sustained without notching the flanges a' .

With both of the constructions shown, an 25 efficient support and self-adjustment of the axle-boxes are secured with the use of ordinary channel-bars and rough-castings, thus producing a very cheap construction.

Having thus set forth the nature of the invention what is claimed herein is:

30 1. In a car-axle mounting, the combination, with a channel-bar, of housings secured to the flanges of the bar, and axle-boxes arranged between the flanges, and having wings projected outward through 35 the said housings.

2. In a car-axle mounting, the combination, with a channel-bar, of housings secured to the flanges of the bar, and axle-

boxes arranged between the flanges and having wings projected outward through 40 the housings beneath the said flanges.

3. In a car-axle mounting, the combination, with a channel-bar, and axle-boxes arranged between the flanges and having wings extended outwardly, of housings 45 attached to the outer sides of the flanges and embracing the said wings.

4. In a car-axle mounting, the combination, with a channel-bar, and axle-boxes arranged between the flanges and having 50 wings extended outwardly, of housings attached to the outer sides of the flanges and embracing the said wings, and means to retain the wings in the housings.

5. In a car-axle mounting, the combination, with a channel-bar, and axle-boxes arranged between the flanges and having 55 wings extended outwardly, of housings attached to the outer sides of the flanges, each having arms extended downward with a 60 socket open at the bottom, and one of the wings fitted thereto, and a lock-bar connecting the arms below the wing and secured by bolts through the arms and lock-bar.

6. In an axle-box mounting, the combination, with a channel-bar, of housings secured to the flanges of the bar, and axle-boxes fitted between the flanges and having each a convex seat fitted to the plate of the channel-bar, and extended nearly to the 70 flanges to resist side-thrust, and having wings extended beyond the ends of the said seat and embraced by the said housings.

In testimony whereof I have hereunto set my hand.

JAMES E. BUSHNELL.
